UNITED STATES PATENT OFFICE.

JOHN W. COOPER, OF HARRISBURG, ASSIGNOR TO CHARLES J. THOMAS, OF PHILADELPHIA, PENNSYLVANIA.

IMPROVEMENT IN PAINT AND VARNISH BRUSHES.

Specification forming part of Letters Patent No. 149,725, dated April 14, 1874; application filed September 19, 1873.

To all whom it may concern:

Be it known that I, JOHN W. COOPER, of Harrisburg, in the county of Dauphin and State of Pennsylvania, have invented certain new and useful Improvements in Paint and Varnish Brushes; and I do hereby declare the following to be a full, clear, and exact description of the invention, such as will enable others skilled in the art to which it pertains to make and use it, reference being had to the accompanying drawings, which form part of this specification.

My invention relates to improvements in paint, varnish, and other similar brushes, whereby economy of manufacture and greater serviceability when new, combined with greater durability, are obtained.

In the accompanying drawings, Figure 1 represents a section, and Fig. 2 a detail view, of parts of a brush arranged according to my invention.

a is the ferrule, having a bell-shaped top, which presents no sharp corners or angles, which enables the operator, when the handle is inserted, to hold and handle the brush with perfect ease and freedom from the annoyance occasioned by the sharp edge presented in ferrules as usually formed, and is provided with the flange *b*. *c* is the handle, made tapering, and of such size that, when driven tight into the ferrule, its inner end is slightly outward of the line *1 1*, Fig. 1. It forms a support to hold in place the dished cup hereafter described, and is provided with the hole *e* for the reception of the shank of the plug. *F* is a dished cap, which fits within the ferrule against the end of the handle, its rim fitting against the upper surface *d'd'*. The bristles *o* rest against this cap, and its shape gives a convex form to the outer end of the brush—a form very much desired, but which is not found in new brushes as ordinarily constructed. It is provided with a central opening, corresponding to the hole in the handle through which the shank of the plug passes. *g* is the wedging and supporting plug, provided with the shank *g'g*, to be driven into the handle. It is made slightly oval, its bulge being on a line with the rim of the ferrule. At its bulge it is nearly severed by the circular gutter *r*, forming the two parts *g'g* and

g², connected by the neck *r'*. The part *g²* is the wedge which holds the bristles *o* in the ferrule. The part *g'* extends below the rim of the ferrule, and serves, when the brush is new and the bristles long, to support and keep said bristles in better shape until the brush becomes worn away, when, by cutting off said end *g'* at the neck *r'*, the remainder of the brush becomes flexible and available for further use. *h* is a removable elastic gum band or sleeve. I use this to hold the bristles together when being inserted into the ferrule. It also operates, in conjunction with the end *g'* of the plug, to hold the bristles firmly in position during the early use of the brush, and prevents the flow and accumulation of paint upon so much of the bristles as it covers. It is turned back or removed entirely, as may be desired, when the brush is worn down so as to necessitate the removal of the end *g'* of the plug. When the bristles are secured in the ferrule the band is drawn up on the flange *b*, and is held by the drip-cup. *i* is a drip-cup, so constructed as to fit neatly over the ferrule and against the flange *b*, and so as to form a wide receptacle, extending below the rim of said ferrule, for the purpose of catching any running or dripping paint when the brush is used in a position to cause the paint to flow toward the handle. Its wide mouth readily permits the paint to run out when the brush is turned down. It fits over and against the flange *b*, and holds securely the gum band or sleeve *h*. It may be removed at pleasure with ease, in which case the gum sleeve is drawn slightly farther up on the ferrule, where it will be held from slipping by its elasticity and the flange *b*. Its position enables the operator to catch the brush well down on the ferrule. The curved flange forming the cup serves as a rest and support for the fingers, and the concave top of the ferrule as a rest for the thumb, thus permitting the brush to be handled with great ease, and with little or no fatigue to the hand.

In the manufacture of my brush I use some suitable material for lining the ferrule which will adhere to and not slip on the metal, which enables me to more perfectly secure the bristles within said ferrule.

In the manufacture of the brush the handle

is driven into place and the cap put into position. The bristles having been properly prepared and placed within the elastic band, the end to be inserted in the ferrule is dipped in shellac and inserted and pressed well against the spherical cap. The bristles are parted in the center by a suitable instrument, and the plug, having its shank previously dipped in white lead or other suitable material, is driven into the handle. The end of the gum band is drawn up over, and the drip-cup put on, the ferrule and pressed down against the flange.

It will be readily seen that my brush can be rapidly constructed, and that it forms a substantial and economical implement, as well as presenting a neat and handsome appearance when completed.

Having thus described my invention, what I claim, and desire to secure by Letters Patent, is—

1. In combination with the handle *c*, ferrule *a*, bristles *o*, and gum band *h*, the wedging and supporting plug *g*, for the purpose specified.

2. In combination with the handle *c*, ferrule *a*, and bristles *o*, the spherical cap *f*, for the purpose specified.

3. The improved brush formed of the ferrule *a*, drip-cup *i*, handle *c*, spherical cap *f*, wedging and supporting plug *g*, and gum band *h*, all arranged as described, and for the purpose specified.

In testimony that I claim the foregoing I have hereunto set my hand this 12th day of September, 1873.

JOHN W. COOPER.
